UNITED STATES PATENT OFFICE.

JOSEPH REX DAVIS, OF CLARKSBURG, WEST VIRGINIA, ASSIGNOR TO REX MANUFACTURING COMPANY, OF CLARKSBURG, WEST VIRGINIA, A CORPORATION OF WEST VIRGINIA.

PISTON RING.

Application filed January 20, 1922. Serial No. 530,596.

To all whom it may concern:

Be it known that I, JOSEPH REX DAVIS, a citizen of the United States, residing at Clarksburg, in the county of Harrison and State of West Virginia, have invented a new and useful Piston Ring, of which the following is a specification.

This invention aims to provide a novel form of spring for a piston ring, the spring being so constructed that it will act by compression to seat the ring, and will act by torsion to expand the ring.

The invention aims, further, to provide a novel form of ring adapted to be used with a spring of the sort hereinbefore alluded to.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in perspective, a ring and a spring constructed in accordance with the invention; Figure 2 is a transverse section showing the device in place in the cylinder and on the piston of an internal combustion engine; Figure 3 is a section showing the device in place in the piston of an internal combustion engine, the cylinder appearing in section; Figure 4 is a diagrammatic transverse section illustrating one of the operations of the spring; Figure 5 is a diagrammatic section of the ring and the spring; Figure 5 being supplemental to Figure 4; Figure 6 is a diagrammatic transverse section illustrating another operation of the spring; and Figure 7 is a section supplemental to Figure 6 and illustrating, further, the operation contemplated in Figure 6.

The numeral 1 marks the cylinder of an internal combustion engine, wherein a piston 2 is mounted for reciprocation, the piston having a circumferential groove 3 defined

by an inner wall 4 and transverse walls 5 and 6.

An expansible ring 7 is seated in the groove 3, the ends of the ring 7 being halved together as at 11, or being otherwise constructed in accordance with accepted principles of internal combustion engine design. The ring 7 has an internal groove 8, defined by a wall 9 disposed at right angles to the axis of the ring, and by a wall 10 disposed at an acute angle to the axis of the ring.

The numeral 12 designates an annular spring, having oppositely projecting loops 14 and 24, the loops being disposed at an acute angle to the axis of the spring. The loops 24 are received in the angle defined by the surfaces 9 and 10 of the groove 8 in the ring 7, the loops 14 being disposed in the angle defined by the walls 5 and 4 of the groove 3 in the piston 2. The ends of the spring 12 preferably are flexed inwardly, as shown at 15, so that they may ride, without catching, in the angle formed by the walls 9 and 10 of the groove 8 in the ring 7. When the ring 7 is not in place, as shown in Figure 1, the loops 14 project, as at 16, beyond one transverse surface 17 of the ring 7.

Noting that the loops 14 of the spring 12 project as at 16 beyond one transverse surface 17 of the ring 7, before the ring is placed in the groove 3 of the piston 2, it will be obvious that, when the spring is in place, as in Figure 4, the loops 14 and 24 of the spring will be compressed, and will react, in the direction of the arrows A to force the ring in the direction of the arrow B, against the surface 6 of the groove 3 in the piston 2, thereby affording an oil tight joint.

Passing to Figure 6, it will be seen that when the spring 12 is in place, the loops 24 will have been swung inwardly, from the dotted line position of Figure 6 to the solid line position thereof, the spring exerting a torque, as indicated by the arrow C, and the loops 24 tending to swing outwardly. As a consequence, the ring will be expanded, in the direction of the arrow D, and will be caused to bear against the inner surface of the cylinder 1.

Generally stated, the spring 12 is so constructed that it acts by compression to seat

the ring, and acts by torsion to expand the ring.

Ordinarily, the ring 7 is placed in the groove 3 of the piston 2, and, then, the 5 spring 12 is inserted endwise into the groove 8 of the ring 7, between the ends 11 of the ring, and, since the extremities of the spring 12 are flexed as shown at 15, the spring will 10 slide, readily, longitudinally into place, it being possible to dispose the extremities 15 of the spring in any desired position with respect to the ends 11 of the ring 7.

As will be evident when Figures 4 and 6 are examined, it will be seen that the loops 15 24 and 14 of the spring 12 define the surface of a cone, and the shape of the spring may be described briefly by alluding to the aforesaid peculiarity in the construction of the spring.

20 What is claimed is:—

1. In a piston ring structure, the combination with the piston having an annular channel for confining the ring, of a ring body having a groove on its inner face presenting an acute angle, and a spring consisting of a body of spring wire provided with oppositely extended loops, the crowns

of opposite loops respectively bearing in the acute angle of the groove and the angle of the channel in the piston. 30

2. In a piston ring structure, the combination with the piston having an annular channel for confining the ring, of a ring body having a groove on its inner face presenting an acute angle, and a spring consisting of a body of spring wire having opposite extended loops which are disposed at an acute angle to the axis of the spring, said spring being confined between the angle of the groove and the angle of the channel. 35

3. In a piston ring structure, the combination with the piston having an annular channel for confining the ring, of a ring body having a groove on its inner face presenting an acute angle, and a spring consisting of a body of spring wire for parts which act compressively and parts which operate by torsion, said parts respectively engaging with an angle of the channel and the angle of the groove in the ring. 40

In testimony that I claim the foregoing as my own, I have hereto affixed my signature.

JOSEPH REX DAVIS.
